UNITED STATES PATENT OFFICE

FREDERICK M. VENZIE, OF PHILADELPHIA, PENNSYLVANIA

BUILDING CONSTRUCTION

Application filed July 23, 1929. Serial No. 380,275.

This invention, generally stated, relates to a building construction and has more especial relation to a floor construction.

One of the great disadvantages in concrete and like floorings is that frames or supports of wood are employed to accept the concrete, which wood greatly depreciates in value as it is used from time to time.

The leading object of the present invention is to provide a temporary flooring construction composed entirely of metal.

A further object of the present invention is to provide a novel form of metallic support for the concrete which is chiefly made of sheet metal and is made up of adjustable parts.

A further object of the present invention resides in the provision of general details of construction and in the arrangement, combination, and connection of parts for attaining the results sought by the foregoing objects.

Other and further objects not at this time appearing will be hereinafter referred to.

The invention consists of the novel construction hereinafter described and finally claimed.

The nature, characteristic features and scope of the invention will be more fully understood from the following description taken in connection with the accompanying drawings forming part hereof, and in which:

Fig. 1, is a view in section taken upon the line 1—1 of Fig. 2.

Fig. 2, is a view in section taken upon the line 2—2 of Fig. 1.

Fig. 3, is a fragmentary view in side elevation of one of the telescopic cement receiving troughs shown in Figs. 1 and 2.

Fig. 4, is a view in section taken upon line 4—4 of Fig. 3.

Fig. 5, is an elevational view of one of the supporting hooks shown in Figs. 1 and 2.

Fig. 6, is an edge view of Fig. 5.

Fig. 7, is a view in perspective of an angle iron shown in Figs. 1 and 2.

Fig. 8, is a fragmentary view in side elevation of a telescopic member for supporting a cement trough as disclosed in Figs. 1 and 2.

Fig. 9, is a view in section taken upon the line 9—9 of Fig. 8.

Fig. 10, is a fragmentary view in elevation

of a channel iron as supported by the hook in Figs. 5 and 6; and

Fig. 11, is a fragmentary view in plan hereinafter referred to.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings in detail, the reference numeral 1 designates spaced metal beams, shown as being I-beams. Supported by each beam 1 is a plurality of pendant, substantially inverted U-shaped hooks or hangers, best seen in Figs. 5 and 6. Each hook or hanger comprises a single piece of heavy wire bent to form a series of horizontal, parallel bars 2 for seating upon the top of a beam 1 and further bent to provide a pair of

pendant, substantially vertical legs 3 which form loops 4 for supporting channel irons 5. The respective ends of the hook or hanger thus bent are inwardly deflected as at 6 to engage beneath the top rail of a beam 1. The channel irons 5 are provided with spaced notches 7 to receive cross-pieces of channel formation and each made up of two parts so

as to have telescopic relation. These cross-pieces are best seen in Figs. 8 and 9 and each comprises channel pieces 8 and 9 are fitted together in nested relation. Thus, a cross-piece

may be increased or diminished in length so as to fit between adjacent beams 1 in accordance with such distance as a pair of beams may be spaced, it of course being understood that the metal cross-pieces are arranged at right angles with respect to the beams 1.

Paralleling the beams 1 and supported by the cross-pieces are spaced angle irons designated 10, best seen in Fig. 7. Each end of each angle iron 10 has stamped therefrom a laterally disposed lip 11 for seating upon the top of

the above described cross-piece. In practice

the flange 12 of an angle iron has riveted thereto as at 13 a cover plate 14 to be herein-after described. Arranged to straddle and seat upon the tops of a pair of cross-pieces 8—9 is a trough-like member of metal, best seen in Figs. 3 and 4. Each trough is preferably made of galvanized sheet metal or the like and is made up of telescopic sections designated 15 and 16. The top edges of a trough are each laterally extended so as to form horizontal members 18 for seating upon the tops of the cross-members 8—9 and the terminal portions of the parts 18 are bent with respect to one another as at 17 so as to have relative interlocked relation without, however, interfering with the telescopic relation of parts. Spanning opposed troughs and supported by the angle irons 10 are the cover plates 12 previously referred to and which are usually formed of galvanized metal or the like, and are riveted as at 13 to said angle irons so as to prevent sliding with respect to the troughs. With the parts thus assembled, reinforcing rods 19 are arranged within the troughs and 25 bent upwardly so as to extend over the tops of the beams 1. Cementitious material 20 is then poured over the cover plates and within the troughs, reinforcing material as expanded metal or the like 21 being employed in the fill. The cover plates 12 are provided with slots 22 to accommodate the vertical parts 3 of the suspension hooks.

With the above described arrangement and construction of parts a simple, efficient, relatively inexpensive and fire proofing structure entirely of metal and cementitious material is provided, the advantages of which are readily apparent. Aside from the relatively cheap construction of parts, the same may be readily assembled by unskilled labor, which is 40 a most important factor in present day labor conditions.

What I claim is:

1. In a building structure of the character stated in which the parts are of metal and cementitious material throughout, a pair of spaced beams, channel irons paralleling said beams, hangers straddling each beam and supporting said channel irons, spaced pairs of telescopically arranged cross-members supported by said channel irons, troughs supported between adjacent pairs of cross-members, a cover plate spanning adjacent pairs of troughs, and a cementitious fill for said troughs, said fill being arranged upon the top of said cover plate.

2. In a building structure of the character stated in which the parts are of metal and cementitious material throughout, a pair of spaced beams, channel irons paralleling said beams, hangers straddling each beam and supporting said channel irons, spaced pairs of telescopically arranged cross-members supported by said channel irons, angle irons arranged between and supported by ad-

jacent cross-members, troughs supported between adjacent pairs of cross-members, a cover plate spanning adjacent pairs of troughs and supported upon said angle irons, said plate being fixed to said angle irons, and a cementitious fill for said trough, said fill being arranged upon the top of said cover plate.

3. In a building structure of the character stated in which the parts are of metal and cementitious material throughout, a pair of spaced beams, channel irons paralleling said beams, an inverted U-shaped hanger formed of wire and provided with pendant loops to accommodate channel irons, hangers straddling each beam and supporting said channel irons, spaced pairs of telescopically arranged cross-members supported by said channel irons, troughs supported between adjacent pairs of cross-members, a cover plate spanning adjacent pairs of troughs, and a cementitious fill for said troughs, said fill being arranged upon the top of said cover plate.

4. In a building structure of the character stated in which the parts are of metal and cementitious material throughout, a pair of spaced beams, channel irons paralleling said beams, hangers straddling each beam and supporting said channel irons, spaced pairs of telescopically arranged cross-members supported by said channel irons, troughs of substantially U-shaped cross-section supported between adjacent pairs of cross-members, said troughs having opposed horizontally disposed flanged portions for fitting over the tops of said cross-members, a cover plate spanning adjacent pairs of troughs, and a cementitious fill for said troughs, said fill being arranged upon the top of said cover plate.

5. In a building structure of the character stated in which the parts are of metal and cementitious material throughout, a pair of spaced beams, notched channel irons paralleling said beams, hangers straddling each beam and supporting said channel irons, spaced pairs of telescopically arranged cross-members supported by said channel irons, troughs supported between adjacent pairs of cross-members, a notched cover plate spanning adjacent pairs of troughs, and a cementitious fill for said troughs, said fill being arranged upon the top of said cover plate, the notched parts of the channel irons accommodating the cross-pieces and the notched parts of the cover plate accommodating said hangers.

FREDERICK M. VENZIE.
